TELEVISION APPARATUS

Alfred N. Goldsmith, New York, N. Y., assignor to
 Radio Corporation of America, New York, N. Y.,
 a corporation of Delaware

Original application November 27, 1941, Serial
 No. 420,629. Divided and this application Sep-
 tember 21, 1944, Serial No. 555,107

7 Claims. (Cl. 88—1)

This invention relates to color television apparatus, and, more particularly, to apparatus for receiving stereoscopic colored images, or receiving monochromatic stereoscopic pictures, or for receiving monocular color images. This application is, furthermore, a division of my earlier filed application, Serial No. 420,629, filed November 27, 1941, for a "Television system."

Stereoscopic and color transmitting systems known to the prior art use the methods of sequentially scanning the images formed by left and right eye separations and three-color component separations, respectively. In the case of color television the component colors are so chosen that the signals resulting from the several component-color scannings, when utilized in each case to reproduce an individual image through correspondingly selected filters, will provide a conjoint image in which the colors are faithfully reproduced. The scanning in such a system utilizes before, or behind the television camera lens a filter disk having three-color component sectors, each sector having a suitable light filter so as to pass only one of the three component colors during each scanning period, which colors, for example, may be blue, green, and red. The output of the transmitter scanning device feeds the train of electrical signals to a suitable amplifier and thereafter the amplified energy is used to modulate a radio transmitter. Such a transmitting system may be in the form of that disclosed by co-pending application, Serial No. 418,109, filed November 7, 1941, entitled "Television system."

The received signals actuate an image reproducing device at the receiving point. In front of the receiver image producing device there is located a similar tri-sector filter disk, each sector being covered with a filter designed to pass one of the three component colors. By rotating the disk at suitable speeds color fusion takes place by the additive process so that the observer of the screen appears to perceive a color picture.

In the prior art the transmission of stereoscopic pictures provides at the transmitter means for transmitting alternately the trains of electrical signals representative of two images of the object to be transmitted, the viewpoints for the images being effectively spaced at the inter-pupillary distance of the eyes. At the receiver the transmitted signals are converted into light images on a viewing surface and immediately adjacent the viewing surface a rotating disk alternately produces a monochromatic (e. g., red) right-eye image of one color and then a mono-

chromatic (e. g., blueish-green) left-eye image of a complementary color, so chosen that light from each of the two filters when mixed together gives the sensation of white light. The viewer is then equipped with a pair of spectacles, one aperture of which is covered with one of the filters and the other covered with filter material of a complementary color. The colors commonly used are, as stated illustratively, red and blueish green.

- 10 It will be readily apparent that under these systems if the red filter is in front of the right eye, the only light which will reach the right eye is that light which passes through the red filter of the receiving disk and the left eye will only receive light passed through the green filter of the disk, assuming that a blueish green filter covers the left eye of the spectacles. Consequently, as the disk revolves, the right eye sees only the image that the right eye would perceive at the transmitting point, while the left eye perceives the image at the receiver which the left eye would perceive at the transmitter. By rotating the disks at the transmitter and the receiver in synchronism, and at sufficiently high speed to eliminate flicker effect, fusion of the two images takes place to provide stereoscopic pictures.

It will be noted that at the receiver there is required a relatively large rotating sector disk in order to provide an image of substantial dimensions, inasmuch as the sector must at some period of the scanning show the entire picture area. Such a receiver is undesirable from the standpoint of cost, since it requires a large driving motor, a supplementary phonic type motor for synchronizing, or, in its place, elaborate synchronizing equipment, a cabinet of increased size to accommodate the disk, together with acoustical treatment to prevent the noise of the driving motor and disk from interfering with the sound reception and magnetic and electric shielding within the receiver as required.

To illustrate the last mentioned point, if an all-electronic receiving system is used, considerable difficulty is experienced in that the magnetic field set up by the motor within the receiver cabinet produces stray fields which interfere with the operation of the deflecting circuits of a kinescope. Again, such a receiver can not, without elaborate changes, such as actually or, in effect, removing the disk and motor, be used for receiving black and white pictures or monocular pictures. Therefore, prior art systems lack flexibility.

By my method and apparatus not only can all these difficulties be eliminated, but the cost can

be substantially reduced, flexibility increased, and at the same time pictures of improved quality can be obtained. My new, novel, and useful method and apparatus of receiving colored stereoscopic pictures or monocular color pictures or stereoscopic monochrome (black-and-white) pictures does away with the motor and scanning disk positioned immediately adjacent the light reproducing device, and, in its stead, utilizes a hand-held viewing device immediately adjacent the eyes of the viewer or observer.

The viewing device comprises a disk having sectorial or segmental apertures, and, in the case of color picture reception, the apertures are covered with appropriate color filters. The disk is mounted within a casing and a very small motor mounted externally on the casing serves to rotate the disk. Two apertures are provided on either side of the casing and are so positioned that they form two pairs of apertures in register with each other and spaced at interpupillary distance of an observer's eye. The number and position of the segments on the rotating disk are so chosen that the same color of the filter is seen in suitable time relation by both eyes. Where stereoscopic pictures are to be received, the filter disk is provided with alternate opaque and light transmitting sectors and the number so chosen that when the eyes of the observer are placed in register with the apertures in the casing, one of the apertures is in register with the light transmitting sector, while the other aperture is occulted. Where colored stereoscopic pictures are to be received the disk comprises alternate sectors which are serially colored in accordance with a predetermined color sequence, while the intermediary sectors are opaque and the number and position of both sectors so chosen that when one aperture is in register with a color sector the other aperture is opaque and, further, when the disk is further rotated, the color sector is replaced by an opaque sector, while the originally opaque sector gives way to a related color sector of the same color sequence as the first named sector. In the preferred embodiment, the related color sector in the preceding sentence is of the same color as the first named sector. In any case, the color and stereoscopic scanning regimes at the transmitter and receiver respectively must be identical and synchronous.

It will be perceived that under these conditions the left and right eye, in the preferred embodiment, alternately see the images of the same color, followed by an obscuration of the viewing surface so that with a similar disk at the transmitter, a person observes, when the disks are rotated in synchronism and with sufficient speed, an image having a three-dimensional perspective and the original colors of the field of view being transmitted, that is, in the case of the transmission of stereoscopic pictures, means are provided at the transmitter for transmitting alternately the trains of electrical signals representative of two types of images of the objects to be transmitted, the viewpoints for which types of images correspond to the left eye and the right eye respectively of the observer and are effectively spaced at the interpupillary distance of the eyes. At the receiver, the transmitted signals are converted into light images on a viewing surface. Thus, there appear on that surface in cyclic repetition the corresponding left-eye and right-eye images. The viewer ob-

serves the viewing surface at an appropriate distance through a rotating disk or shutter which alternately occults or obscures the vision from the left eye of the observer and vision from the right eye of the observer. This occulting action of the rotating disk immediately adjacent to the observer is in appropriate synchronous relation and phase relation to the appearance on the viewing surface of the left-eye and right-eye images, respectively, in such fashion that left-eye vision of the observer is unobscured during the period that a left-eye image appears on the viewing surface, and right-eye vision of the observer is unobscured during the period that a right-eye image appears on the viewing surface. Thus the observer sees with each eye, at the viewing surface, only the images which that eye would perceive in front of the actual three-dimensional subject which was scanned at the transmitter. Accordingly, the observer sees a stereoscopic monochrome picture provided the disks at the transmitter and receiver are in synchronism and like phase relationship and rotate at a sufficiently high speed to eliminate any flicker effect and to cause fusion of the images seen by the right and left eyes of the observer as required to provide stereoscopic vision.

It is a portion of my invention to introduce color into the stereoscopic pictures produced according to the preceding principles by presenting to the view of the observer a rapid succession of component-color stereoscopic pictures. Thus, I may first present a left-eye blue picture to the left eye of the observer followed immediately by a blue right-eye picture submitted to the right eye of the observer. At this point, the observer would have an impression of a stereoscopic blue picture. However, immediately thereafter there is presented to the left eye of the observer a green left-eye image, immediately followed by the presentation to the right eye of the observer of a green right-eye image. This last mentioned pair of images would therefore in themselves, and in the absence of any other pictures, give the observer the impression of a green stereoscopic picture. However, to complete a tricolor stereoscopic scanning or image cycle, there is immediately thereafter presented to the left eye of the observer a red left-eye image, immediately following which there is presented to the right eye of the observer a red right-eye image. Accordingly, the observer next gets the impression of a red stereoscopic image.

The preceding viewing regime has therefore presented to the observer in rapid succession blue, green, and red stereoscopic pictures, such cycles of image presentation being then repeated as required. If the entire scanning cycle above described, involving as it does the presentation of six different images (corresponding respectively to two viewpoints separated by the interpupillary distance, each viewpoint being presented in three component colors), occurs within a sufficiently brief time, tricolor fusion as well as stereoscopic fusion occurs in the eye and brain of the observer. Accordingly, the observer will see a colored stereoscopic picture under these conditions and as a result of the particular image-presentation regime herein described.

Accordingly, it is the object of my invention to provide a television apparatus capable of reproducing colored stereoscopic pictures or other images.

Another object of my invention is to provide a

new, simplified receiving method for receiving monochromatic stereoscopic pictures.

Another object of my invention is to provide a new and simplified television system for reproducing monocular color images.

A further object of my invention is to provide a new viewing device which may be hand-held for converting black and white images into colored stereoscopic images, colored images, or stereoscopic images.

Other objects of my invention will become apparent upon a reading of the following detailed description, in which reference will be made to the drawings; wherein,

In the drawings,

Figure 1 represents somewhat diagrammatically a color transmitting and receiving television system embodying the principles and apparatus of my invention;

Figure 2 shows in elevation a viewing device embodying my principles and suitable for viewing color and stereoscopic pictures;

Figure 3 shows a side view of the viewing instrument shown in Figure 2;

Figure 4, Figure 5, Figure 6, and Figure 7 show disks suitable for use in my viewing device for viewing stereoscopic pictures;

Figure 8 and Figure 9 show filter disks which are suitable for use in my device for viewing color pictures; while Figure 10 shows a disk suitable for use in my viewing device for viewing colored stereoscopic pictures.

For purposes of explaining the principles of my invention I have shown in Figure 1 a television system for transmitting colored images which embodies a method and apparatus which will be described in detail below. It will be appreciated that in order to make the explanation as simple as possible the system shown is for transmitting colored pictures. The same principles, however, are applicable to the transmission of stereoscopic pictures and for transmitting colored stereoscopic pictures.

Referring now to Figure 1, there is shown at 111 the colored object to be transmitted. An optical system 113 produces an image on the scanning device 115. The scanning device is shown schematically, merely by way of example, as an iconoscope. A suitable deflection system for controlling the scanning beam is shown at 127. Interposed between the optical system 113 and the scanning device 115 is a tricolor filter disk 117 driven by a motor 118. The filter disk is provided with three filters 121, 123, 125, which may be of any suitable tricolor combination, such as, for example, blue, green, and red. A suitable synchronizing system 128, controlled by or related to the field synchronizing or deflecting system 127, serves to operate the motor synchronously with the deflection system. For purposes of illustration, it will be assumed that an odd-line interlaced system of 120 fields and 40 frames is used. Signals from the scanning device 115 are amplified by the amplifier 125 and transmitted by way of transmitter 131 to the transmission medium by the antenna 133.

It will be appreciated that the transmitter will embody a modulator and means for reinserting a D. C. component in the event that the D. C. component is not transmitted by the amplifier 122. It will also be appreciated that the usual and conventional blanking and synchronizing signals are also transmitted. In operation, there will be thrown on the scanning device 115 an

image whose color will be determined by the filter 121 and, for purposes of illustration, it will be assumed that the filter 121 is blue. This blue image is scanned as the first field, and, consequently, will be an odd-line picture. Following the completion of the scanning of the blue image, the filter 123, assumed green, is interposed between the optical system and the scanning device to produce the green component image of 10 the object 111 on the scanning device 115. This is scanned as the even field. Following the completion of this scanning of the green image, the filter 125, assumed red, produces a red image on the scanning device which is scanned as an odd field image. Following the completion of this scanning, the blue filter 121 produces a blue image, which is scanned as an even field, while the subsequent repetition of the above steps produces green scanned as an odd field and the red scanned as an even field, and this cycle is thereafter repeated.

Due to the retentivity characteristics of the eye, there will thus appear an image at the receiver, when appropriate steps are taken, which bears a faithful reproduction of the colors of the object 111. This is brought about in my invention by receiving the signals at the antenna 135 and detecting them in a conventional television receiver 137. The video output signals of the receiver 137 are then fed to a kinescope 141 having a screen or target 141, which screen preferably luminesces with substantially white light when impacted by the modulated scanning beam. A deflection system 151 produces the vertical and horizontal scanning of the beam in synchronism with the scanning action at the transmitter. There will thus be reproduced on the screen 141 a series of black and white fields which are interlaced, and which black and white fields contain 30 the color information transmitted. Hand-held (or otherwise locally supported) and interposed between the eyes of the observer 145 and the screen of the kinescope 141 is my viewing device 143.

45 The viewing device comprises a filter disk driven by a motor, which motor bears a synchronous speed and phase relation to the driving motor 119 at the transmitter. The filter disk contains blue, green, and red filters in sequence and in such numbers that there will appear in front of two apertures to which the eyes are placed pairs of identical filters during the rotation of the disk, in the order of blue, green and red, in the case of the example shown. Means are provided for properly phasing the filter disk of the viewing device 143 with respect to the filter disk 117. Thus, in operation, if the blue filter 121 is effective at the transmitter, then before each of the apertures 161 there will appear blue filters so that the observer sees the black and white field reproduced on the screen 141 as a blue image, followed, in turn, by green and red images. The cycle is then repeated and, since the line and frame frequency is high enough, color fusion takes place by the additive process to produce a final image which is colored in accordance with the colors of the original object 111.

70 In the deflection system 151 there is shown schematically a switch 149 and contacts 153 and 155 for selecting appropriate values of constants of the deflecting system so that alternatively one may receive black and white images transmitted from a station transmitting conventional black and white signals, when the switch is in a posi-

tion 155, or receive the transmission from a station transmitting color television signals, when the switch is in the position 153. Other switch positions are provided, 157 and 159, to afford choice of constants suitable for receiving, for example, colored stereoscopic pictures or monochromatic stereoscopic pictures, that is to say, a switch is provided for selecting the circuit constants of the horizontal and vertical sweep circuits necessary to give the appropriate lines, 10 fields, and frames necessary to receive a given type of picture. Thus, for example, black and white pictures would embody 525 lines odd-line interlaced with sixty fields and thirty frames per second and would be received when the switch is in the position 155. Colored pictures would be received when the switch is in the position 153, with, for example, about 375 lines odd-line interlaced with 120 fields and 40 frames per second. This would insure substantially the same band width of frequencies, while maintaining approximately the same relation of horizontal to vertical resolutions. For color stereoscopic pictures the number of fields would have to be double the number used for the transmission of color pictures or 240 fields per second, as will be explained below, and, in which case, the switch 149 would have to select a different set of constants for the deflection system 151 corresponding for the same band width of frequencies to the smaller number of about 275 lines. However, it must be understood that different band widths of frequency may be made available for the various types of transmission, in which case the preceding numerical illustrative values will not hold, and the switch 149 will also control received band width appropriately for each type of transmission.

In Figures 2 and 3 there is shown in somewhat more detail in elevation and side view a suitable viewing device embodying the principles of the invention. The motor 11, mounted on suitable brackets 9 and 10, serves to rotate the color disk 21 mounted on the shaft 2. It will be appreciated that while the disk is shown being driven by the motor shaft itself, suitable gearing may be interposed between the motor and the filter disk 21. The brackets 9 and 10 are mounted on a cylindrical casting 13 which is preferably lined with sound absorbent material 14. Inside the casing is the color disk 21 on which are the tricolor filter elements 16, 15, 20, 19, 18, 17. These are sequences of red, green, and blue so that the rotation of the color disk in the direction 12 brings before the eye apertures 3 and 4 the identically colored sectors corresponding to the right and left eyes of the observer, respectively, in the same sequence as the corresponding color scannings at the transmitter and the same rate of appearance as the corresponding color fields follow each other and spaced at proper interocular inter-pupillary distance. Suitable shields 3 and 4 may be mounted on the viewing side of the casing 13 to prevent extraneous light from reducing the contrasts of the observed pictures.

Of course, it will be appreciated that clear plastic or glass may be used to cover the apertures 31, 33, 32, 34, to prevent dust and dirt from falling on the filter sectors of the rotating disk, as well as to prevent the sound of the disk rotating within the casing from escaping. While the eye shields have been shown in fixed position, it will be appreciated that the shields may be made adjustable laterally in order to accommo-

date people having different interocular or inter-pupillary distances.

If there were only three color sectors on disk 21, it would not be convenient to have filters of the same color simultaneously in front of both eyes of the observer, if the disk is to have minimal dimensions. This difficulty is overcome by preferably providing an even number of sets of the three filters on the disk, for example, six filters, twelve filters, or eighteen filters, and so on. Increasing the number of sectors, however, may produce an effect comparable to aperture distortion, that is to say, that the total time taken for a filter to entirely enter the field of view may be a large portion of the total time that any filter remains in view. Under these conditions, since the entrance of the filters for each eye is in the opposite direction, there may appear to the observer an image in which a relatively dark band travels across the picture in the vertical direction. This effect, however, is rendered harmless by insuring that the time of entry of the leading edge of the filter section (time of apparent sweeping of the leading edge across the field of view) is but a very small proportion of the time that the filter actually covers the whole field. Practically, this is brought about by insuring that each filter sector is bounded by sides whose included angle is large relative to the angle subtended by the tangents to the pupillary apertures passing through the center of rotation of the disk. Thus, for example, with 120 color fields per second the motor may have, for direct drive of a six-sector disk, three pole pairs for pairs for 60 cycles per second power supply; that is to say, the motor should operate at 1200 R. P. M.

The power supply line 28 to the motor 27 may be passed downward through the interior of the hollow and light handle 30 for supporting the viewing device, leaving at the bottom of the handle 30 and terminating in an extension cord and plug so that the viewing device may be plugged into any convenient available source of supply energy of correct frequency. A suitable push-button switch or phasing interruptor is connected in series with the power supply line. The switch is normally in a closed circuit position and is open only when pressure is applied thereto. Momentary pressure on the button 23 therefore causes the circuit to open permitting the motor to lose speed momentarily and hence can be used for "slipping" the rotor until it is in phase with the filter disk at the transmitting point. Moreover, slipping adjustment can be alternatively or additionally provided by mounting the motor 11 so that it can be bodily rotated by hand about its axis with respect to the casing 13. This also permits accurate phasing of the viewing device with a transmitter disk so as to take account of the time delay between the transmission and reception of the signals.

Furthermore, as a matter of convenience and for steadiness of viewing, the viewing device may be provided with an adjustable chin rest 28, which is slidably adjustable along the holder or handle 30. The chin rest may be held in position, once the adjustment is made, by means of a knurled screw 29.

A suitable color disk corresponding to the disk 21 of Figure 2 and Figure 3 is shown in Figure 8 where the sectors 73, 72, 71 correspond respectively to the sectors 20, 15, and 16 of Figure 2. It will be noted that in Figure 8 the location of apertures 79 and 78 lies on a horizontal diam-

eter and, consequently, represents a horizontally centered type viewing device. An alternative form is shown in Figure 9, in which the eye pieces 77 and 78 no longer lie on the horizontal diameter of the disk, but both of the apertures 77 and 78 lie on one side of the diameter. This represents the non-horizontal centered type disk. It will be noted that under such conditions the total number of sectors is an odd number. The modification of the disk shown in Figure 9 is useful where the size of the motor for driving the disk becomes comparable with the interocular distance. Under these conditions, to use a disk of the type shown in Figure 8 would mean that a portion of the field viewed by the eye would be obscured by the motor. By placing the eyepieces below the motor, as shown in Figure 9, this difficulty is avoided. It will be appreciated that while the number of sectors is shown in the case of Figure 8 as being six that actually the number of sectors may be increased to 12, 18, etc., in which series the sequence of blue, green, red is followed, while in the case of Figure 9 the number of sectors may be, in addition to that shown, 15, 21, etc. It is desirable, however, generally speaking, to keep the number of the sectors minimum and to use a maximum motor speed necessary to insure proper synchronism between the disk of the viewing device and that of the transmitter, since such a combination results in the smallest "aperture distortion" effect.

Turning now to the transmission and reception of stereoscopic pictures in monochrome, I have shown in Figure 4 a horizontally centered type disk of two sectors; one of the sectors 43 is blank or may be covered with transparent material, while the other sector 44 is opaque. As illustrated, light will pass through the eye pieces 41 and will be completely blocked through the eye piece 42. As a consequence, only one eye receives at a time a light image. At the transmitting point, a stereoscopic television system transmits pictures which are representative of a scene as it would be seen with the right eye and the left eye alternately. Such a system may take the form of that disclosed in Zworykin U. S. Patent 2,107,464, for "Television system." Due to visual or subjective fusion of the two images, the alternate viewing provides a stereoscopic effect that is well known in the art.

In Figure 5 there is shown a six-sector horizontally centered type disk in which the sectors are opaque and light transmitting alternately.

In Figure 6 there is shown a non-horizontally centered type disk of four sectors, in which eye pieces are shown at 55 and 54, while in Figure 7 there is shown an eight-sector non-horizontally centered type disk with the eyepieces located at 59 and 60. It will thus be appreciated that for the horizontally centered disk the number of sectors may be 2, 6, 10, 14 and so on, while for the non-horizontally centered type the number of sectors would be one chosen from the series 4, 8, 12, 16, etc.

In Figure 10 there is shown a disk of the non-horizontally centered type suitable for receiving colored stereoscopic pictures. In this picture the disk has sectors which are composed of alternately light transmitting sections and light occulting sections. The light transmitting sectors have band-pass spectral transmission ranges and may, for example, comprise blue, green and red filters. In Figure 10, for example, the sectors 83 and 84 are blue. The sectors 81 and 87 are green and the sectors 85 and 86 are red. The eye pieces

88 and 102 are positioned above the horizontal diameter of the disk. The sectors 80, 82, 84, 86, 88 and 100 are opaque. Thus, as the disk rotates, it will be clear that the left eye will see the image corresponding to the view that would be seen by the left eye of an observer holding a red filter before his eye.

With further rotation of the disk the aperture transmitting light to the left eye is occulted by the opaque section 80, while simultaneously the right eye has placed in front of it the red section of filter 85 and will see the image corresponding to the view that would be seen by the right eye of an observer holding a red filter before his eye. This pair of viewings or images will therefore form a red stereoscopic image. Further rotation of the disk would similarly provide a green stereoscopic image, and still further rotation would produce a blue stereoscopic image.

By rotating the disk at sufficiently rapid rate, subjective color fusion of the images takes place so that the observer perceives a color stereoscopic representation truly indicative of and corresponding to the original object and its surrounding color and spatial relationships. The color stereoscopic transmitting station may be in the form of the type described in the Zworykin Patent above identified to which there would be added before the single transmitting pickup device a color sector disk for providing for the following cyclically repeated scannings: 1. red scanning of the left eye view; 2. red scanning of the right eye view; 3. green scanning of the left eye view; 4. green scanning of the right eye view; 5. blue scanning of the left eye view; 6. blue scanning of the right eye view.

It will be appreciated that only three sectors in the transmitting filter disk would be required and the rotation of the disk would be such as to insure that the speed of rotation of the disk is such that the time duration during which the red filter, for example, covers the tube is equal to the time to provide complete scannings for both the right and left eye. Where two transmitting tubes are provided a disk similar to the one shown in Figure 10 may be used so that one tube is occulted during the time the other tube has a filter in front of it, and thereafter the second tube is occulted, while the first tube has a filter of the same color covering it. It is believed that since these principles are so well understood, that it is unnecessary to illustrate such a transmitter in order to provide a complete and adequate understanding of the invention.

In certain cases four-color component pictures may be used for color separation purposes, according to the Zander, Hering, or Ladd-Franklin theories, in which cases the "primaries" are red, yellow, green, and blue. Such a quadri-color process may have a non-horizontally centered viewing arrangement and a number of sectors chosen from the series 8, 12, 16, 24, etc. For stereoscopic quadri-color television the disk may have 8 color sectors alternating with 8 opaque sectors, or, any number of color and opaque sectors chosen from the series 12, 16, 20, etc.

For ideal operation of the colored stereoscopic pictures, that is, one in which the image reproduction is apparently flickerless, it is desirable that there should be six times as many fields per second as required for monocular black and white television, or, in accordance with present standards, 360 fields per second. This will be apparent when cognizance is taken of the fact that if only 60 color fields per second were used, such

as in black and white television, then the color and occulting flicker effects would be intolerable, since each eye would be receiving a total of only ten frames per second (three color fields alternated by three black fields constituting one complete picture). For this reason, therefore, the number of fields per second for colored stereoscopic pictures must be increased.

Various alterations and modifications of the present invention may become apparent to those skilled in the art and it is desirable that any and all such reasonable modifications and alterations be considered within the purview of the present invention.

Having now described the invention, what is claimed is:

1. A hand-held viewing device for color television image production observation comprising a handle support member, a housing element having a pair of viewing apertures spaced from each other at substantially interpupillary separation, said housing element being supported by the handle, a rotary color filter disk unit having at least a pair of series of sectorially shaped color filter areas with each series including a filter element of each component color of the image to be viewed, said color filter disk unit being so located within the housing that like color filter areas are aligned with each of the viewing apertures simultaneously to be viewed therethrough, a sound absorbing material lining the said housing element, a drive motor means supported from the housing element for rotating the color filter unit and bringing the color filter elements of the disk successively into registry with the viewing apertures, a phasing interruptor element positioned on the handle element to control, with brief actuation, the said motor and thereby align like component color filter areas substantially instantaneously with the viewing apertures to phase filter rotation drive with the image production on an area to be viewed and means adjustably supported on the handle support means for resting the observer's chin and permitting thereby fixed positioning of the eyes of an observer relative to the viewing apertures in the housing element.

2. A hand-held viewing device for stereoscopic television image production observation comprising a handle support member, a housing element having a pair of viewing apertures spaced from each other at substantially interpupillary separation, said housing element being supported by the handle, a rotary color filter unit having a plurality of sectorially shaped color filter areas formed to include at least one filter element of a color corresponding to each component color of an image to be viewed and an opaque filter area separating each color filter sector, said color filter disk unit being so located within the housing and so positioned relative to the viewing aperture that a color filter area is aligned with one of the viewing apertures simultaneously with the alignment of an opaque filter area with the other aperture so that an image plane is observable alternately through the apertures and in different colors, a drive motor means supported from the handle and contained within the housing for rotating the color filter unit and alternately bringing the color filter elements successively into registry with one of the viewing apertures and an opaque section alternately in the path of the other aperture, a phasing switch unit located within the handle element to control the said motor and thereby align one of

component color filter areas substantially instantaneously with a predetermined viewing aperture so as to phase filter rotation drive with the image production on an area to be viewed.

3. A hand-held viewing device for color television image production and observation comprising a handle support member, a housing element having a pair of viewing apertures spaced from each other at substantially interpupillary separation, said housing element being supported by the handle, a rotary color filter disk having at least a pair of series of sectorially shaped color filter areas with each series including a filter element of each component-primary color of the image to be viewed, said color filter disk being so located within the housing that like color filter areas are aligned with each of the viewing apertures simultaneously and viewed therethrough, a drive motor means supported from the handle for rotating the color filter unit and bringing like color filter elements successively into registry with the viewing apertures and a phasing switch unit located within the handle element to control the said motor and thereby align like component-primary color filter areas substantially instantaneously with the viewing apertures to phase filter rotation drive with the image production on an area to be viewed.

4. A viewing device for binocular stereoscopic observation of images created upon an observation area comprising a disk element having at least one series of cyclically recurring sectorially shaped color filter elements of each component color of a multicolor additive system and said disk also having a series of sectorially shaped opaque sections of a size comparable to each color filter element and arranged so that each component color filter element is separated from each preceding and succeeding component filter element of the series by a single opaque section, a support means for positioning said disk unit for rotation so that the observation area may be observable along two paths through spaced individual sectors of the disk, and a drive means for rotating said disk so as to bring color filter elements and opaque occulting elements alternately and successively into the two observation paths in a cyclically recurrent order so that the centralmost point of a color filter area coincides with the axis of one observation path simultaneously with coincidence of the axis of the other observation path and the centralmost point of an opaque area, and vice versa.

5. A hand-held locally supported binocular viewing device comprising a substantially cylindrical casing element, a sector disk positioned for rotation within the said casing, the sectors of said disk having different chromatic light absorption characteristics and being arranged in a cyclically recurrent order, motor means integral with the said device for rotating the disk and the therewith associated sectors, said casing also having a pair of apertured means for permitting the transmission of light rays from one side of the casing to the other through the said disk, a handle element affixed to the said casing to serve as a support therefor and for the housed elements, and a phasing interrupter unit positioned on the handle to control, with brief actuation, the said motor and thereby to align like component color filter areas substantially instantaneously with the viewing apertures to phase the filter rotation drive with the related color in which the image is to be produced on an area to be viewed.

6. A hand-held viewing device for color stereoscopic image observation comprising a handle support member, a rotary filter element having at least one series of sectorially shaped color filter elements each series including at least one unit of each component color of a multicolor additive system, a series of sectorially shaped opaque image occluding sections of comparable size to each component color filter element for separating each component color filter element from each preceding and succeeding color filter of the series, a housing element having included therein a pair of viewing apertures, said housing being supported from the handle and enclosing the rotary filter element, and the apertures within the housing being spaced at substantially interpupillary separation of an observer, the said apertures also being so located relative to the housing and the enclosed rotary filter that instantaneously a single filter element of the component color series is revealed through one aperture simultaneously with the exposure of an opaque section through the other aperture and vice versa for viewing, a drive motor means also supported from the handle and connected for rotating the said filter element and causing the color filter elements and the opaque sections to pass the viewing apertures, and a phasing interruptor unit positioned on the handle to control, with brief actuation, the said motor and thereby to align the component color filter areas substantially instantaneously with the viewing apertures so as to phase the filter rotation with the image production on an area to be viewed.

7. A hand-held viewing device for color stereoscopic image observation comprising a handle

support member, a rotary filter element having at least two series of sectorially shaped color filter elements of which each series of color filters includes one unit of each component color of a multicolor additive system, a series of sectorially shaped opaque image occluding sections each of a size comparable to each component color filter element, and opaque sections being located on the filter between each color transmitting element for separating each component color filter element from each preceding and succeeding color filter of the series, a housing element for the rotary filter element supported upon the handle, said housing having included therein a pair of viewing apertures which are spaced at substantially interpupillary separation of an observer, the said apertures also being so located relative to the housing and the enclosed rotary filter that instantaneously a single filter element of the component color series is revealed through one aperture simultaneously with the exposure of an opaque section through the other aperture and vice versa for viewing, a drive motor means also supported from the handle and connected for rotating the said filter element and causing the color filter elements and the opaque sections to pass the viewing apertures so that the successive colors of the filter appear in like order before each aperture, and a phasing interruptor unit positioned on the handle to control, with brief actuation, the said motor and thereby to align the component color filter areas substantially instantaneously with the viewing apertures so as to phase the filter rotation with the image production on an area to be viewed.
